MOISTUREPROOF CONTAINER

Paul S. Pittenger, Philadelphia, Pa., assignor to
Sharp & Dohme, Incorporated, Philadelphia,
Pa., a corporation of Maryland

Application January 2, 1936, Serial No. 57,102

3 Claims. (Cl. 220—27)

This invention relates to hermetically sealed containers or tins. It includes containers or tins which are completely moistureproof, yet are provided with frangible or easily perforable wall sections, which, when fractured or pierced to open the containers, offer no sharp cutting edges which might cut the fingers, etc.

One object of the present invention is to provide a sealed container with a frangible wall section, which is nevertheless completely moistureproof. The only moistureproof containers of which I am aware are containers having no porous or permeable wall sections, and in which all seams are hermetically sealed. Containers having wall sections of paper, parchment, regenerated cellulose, or the like are not moistureproof.

It has been proposed to provide containers or tins with wall sections of frangible material, such as paper or parchment, seamed to the other sections of the container. Such wall sections, however, do not prevent the ingress of moisture, but only retard it. Even paper or parchment coated with paraffin fails to prevent the entrance of moisture completely. The problems encountered due to this penetration of moisture are particularly acute where the containers are used for shipping and storing hygroscopic materials such as hard candies, coughdrops, coffee, etc., which deteriorate in the presence of moisture, and which are shipped or stored in tropical climates, where they may be exposed to air almost saturated with water vapor at relatively high temperatures for prolonged periods of time. For such use, containers which rely upon a wall surface of paper or the like, even so-called "moistureproof" paper, are not sufficiently moisture-resistant to properly preserve such hygroscopic materials.

Accordingly, it has been common practice to package and ship hygroscopic materials in containers having all metal surfaces, hermetically sealed. Where it is desirable to afford means for opening the container without resort to a can-opener, or the like, it has been common to seal the container by means of taggers tin or the like, and to provide either a key with which to remove a section of the container wall, or to provide an auxiliary cover equipped with a cutter adapted to remove the sealed top of the container by cutting. Such containers, when opened, have a sharp jagged edge and frequently are responsible for painful cuts, etc.

It has also been proposed to provide containers with a wall section of metal foil, to pro-

vide a readily frangible opening. Such foil, however, in order to allow economical handling, and to be capable of forming a tight seal with the other sheet metal of which the container is made, for practical and large-scale operation, must have appreciable thickness and be quite heavy, and hence its use is relatively expensive. This is particularly true in cases where it is desired to print or lithograph on the foil, as it must then be made of aluminum or the like of sufficient weight to burnish and polish.

My invention provides a container with a wall section which is completely moistureproof, which is frangible, and may be removed or fractured without the use of a cutting tool, which may carry printed or lithographed matter, which is economical and easily handled and shipped, and which may be hermetically sealed in place by a simple operation.

The containers produced in accordance with the present invention have the further advantage that they may be filled before the frangible top or section is applied. Thus, as in the usual case, the container may be made with a bottom and sides, then filled, and the frangible section applied as the top, and sealed in place.

Containers heretofore provided with a frangible top, as of paper or the like, sealed in place, have generally been assembled by forming the top and sides, filling the container from the bottom, and then sealing the bottom in place. The frangible section in such containers has been generally used to insure that the product in the container is that originally packed there, and is not spurious. Such seals have generally been secured by interior seams, and have not been relied upon to protect the material in the container from moisture. Containers of this type not only have the disadvantage of having to be filled from the bottom, but also must be made with a bottom seam, whereas, in my containers, the bottom and sides of the container may be made from a single sheet of metal, stamped in a single operation.

I use for the frangible wall section a composite or laminated sheet of material, composed of an extremely thin sheet of metal, fastened securely to a sheet of paper, and backed by cardboard or heavy paper. The metal foil attached to paper is commercially available and is relatively cheap. The metal foil which I use is extremely thin and is so frangible that without the paper to which it is fastened it cannot be handled or shipped, at least without such precautions as to render the cost of its use for any purpose prohibitive.

This thin metal foil, however, in spite of its extreme thinness, possesses the desirable property of being moistureproof.

This metal foil consists of an extremely thin sheet of metal which may be produced by cold rolling a suitable alloy, i. e., an alloy having the property of cold flow without cracking. One suitable foil is produced from an aluminum alloy, and is rolled to extreme thinness. It is flexible and highly polished. It is well adapted for printing or lithographing. It is to be understood that the process by which the foil is made, or its composition, is no part of my invention, but that any foil having the desired properties may be used.

The foil and paper to which it is fastened are mounted upon cardboard or heavy, stiff paper, to provide a sheet which is sufficiently stiff to be handled with facility, and sufficiently thick to allow proper sealing. Very thin sheets can not be used with any assurance where a moisture-proof seal is required, as variations in the mechanical operations of rolling and crimping, or double sealing, may result in an improper seal, whereas with the sheet material which I use, the cardboard or heavy paper backing acts as a compressible gasket and insures a proper seal. The laminated sheet, of metal foil, paper, and reinforcement, is preferably about $\frac{1}{8}$ inch thick.

While it is necessary to have the cardboard or heavy paper backing for the wall section at the periphery of the section, where it is sealed, I find it is also advantageous not to have the reinforcement coextensive with the section, but to have a portion of suitable size with no reinforcement, i. e., to have a suitable section in which the wall consists only of the metal foil and the paper to which it is attached. Such a construction is of great advantage, in that it affords a container which is readily opened, only pressure of the fingers being required at the unreinforced section to burst it and expose the contents of the container. It is also desirable, where on unreinforced portion of the wall section is provided, to indicate in a suitable manner the location of the unreinforced portion, as by printing or lithographing, so that no difficulty in opening the container may be encountered. For this reason, the thin, burnished metal which I use is advantageous, because of its suitability for printing or lithographing. It is desirable, where such construction is used, to provide a protection for this weak wall section, as by a friction cover, or the like.

The invention will be further illustrated by reference to the accompanying drawing, which illustrates a container which embodies the invention, although the invention is not limited thereto. In the drawing,

Fig. 1 is a perspective view of a container bottom and sides, adapted to receive a frangible section for a top;

Fig. 2 is a perspective view of the bottom of a frangible section adapted for use as the top of the container of Fig. 1;

Fig. 3 is a cross-sectional view of the frangible section of Fig. 2;

Fig. 4 is a cross-sectional view of an assembled container; and

Fig. 5 is a detail view showing an alternate method of seaming.

Fig. 6 is an enlarged, broken, fragmentary, vertical, transverse section through the laminated sheet 16.

Referring to Fig. 1, 10 represents a stamped

sheet metal box, open at the top, intended to form the bottom and sides of a rectangular container for hygroscopic materials, etc. It has a bottom 11, and sides 12, integrally formed from a single sheet of thin metal. The bottom and sides have 5 corrugations 13, intended to strengthen the container and increase its rigidity, so as to allow relatively thin sheet metal to be used, and still have sufficient strength to withstand the pressure exerted in crimping and rolling the upper edges 10 of the box. An internal shoulder or bead 14, is formed near the top of the box by an inward fold of the side walls. The side walls project above this shoulder a short distance, as shown at 15.

Adapted to rest on shoulder 14, and to fit snugly into the top opening of the box is the laminated sheet 16 shown in Figs. 2 and 3 and in broken, fragmentary, vertical, transverse section in Fig. 6. This sheet is formed from an extremely thin sheet of highly polished aluminum alloy fastened to a sheet of paper by means of an adhesive. This dual sheet, consisting of thin metal foil 17 and flexible paper 17a, is backed and supported by cardboard, or heavy stiff paper 18 (see Fig. 6). This backing is not coextensive with the composite metal-paper sheet, but is formed from a sheet of cardboard or heavy paper of the same outside dimensions as the composite paper-metal sheet, but with a hole in the center, 30 so that the composite sheet is supported or backed at its periphery, but has a weak or unreinforced portion at the center, which facilitates opening the container. This cut-out section of the backing is shown at 19 in Figs. 2 and 3. Top 35 section 16 is turned up at the edges to form a flange, with the cardboard on the outside, as shown at 20, so that, when it is dropped in place in the container box, with the metal foil side up, the flange lies against the sides of the box for a 40 short distance above the shoulder 14.

Fig. 4 illustrates the assembled container, showing the details of securing the frangible top in place, in the preferred manner. Here 10 represents the bottom and sides of the container formed from a single sheet of metal, with strengthening corrugations 13. Frangible section 16, composed of a thin metal foil 17 with paper backing 17a, supported by heavy paper or cardboard 18 at the periphery, but not at the center, as shown at 19, rests on shoulder 14, with the flange 20 lying against the sides 15 of the box. The upward extensions of the sides, above the shoulder, are bent over and crimped against the metal of the composite sheet, and so as to compress the thick cardboard or paper backing, as shown at 21, to form a tight, moistureproof, all-metal hermetic seal. A sheet metal cover, 22, friction fit, is then applied to the sealed box.

Fig. 5 illustrates another manner in which the 60 frangible top may be sealed into the container. In this embodiment of the invention, the frangible section 23 is of the same construction as that of Figs. 2 and 3, except that it is not provided with an up-turned flange at the periphery. 65 The section fits snugly into the box, and rests upon shoulder 14, the upper edge of the box being rolled over and crimped down upon the frangible section as shown at 24 to form a tight seal. The compression of the cardboard or thick paper support, and the tight fit of the metal foil with the crimped edge of the box insures a continuous metal seal.

Containers produced in accordance with this invention have many advantages, and may be 75

used for diverse purposes in various embodiments. They are of particular advantage for use with hygroscopic materials, or materials which it is important to protect from ingress of moisture or air, such as various food and medicinal products, candies, etc. which are desirably marketed in hermetically sealed, moistureproof containers, which, while they effectively protect the contents, are nevertheless easily opened without resort to can-openers or the like, and which, when opened, are free from sharp cutting edges.

5 The new containers have the further advantage that the frangible sections may be applied after the container is filled, and may be the last section applied in assembling the container, and before applying the cover. Further, the containers are simple and easy to produce and are particularly advantageous where containers of inconsiderable depth are desired, as all of the 10 container, save the frangible section, may be stamped from a single sheet of metal, and the container may be free from seams except where the frangible section is secured in place.

15 I claim:

20 1. A hermetically sealed, moistureproof container having a bottom, sides and a top, having a wall section comprising extremely thin polished metal foil, said metal foil having insufficient stiffness and strength for use as a wall section without reinforcement, adapted for printing and lithographing, adhesively fastened to a sheet of paper, reinforced by cardboard or heavy stiff 25

the entire area of said section, said unreinforced area having a strength such that it may be burst by the pressure of the fingers alone.

2. A frangible wall section adapted for use in a hermetically sealed, moistureproof container comprising a sheet of extremely thin polished metal foil, said metal foil having insufficient stiffness and strength for use as a wall section without reinforcement, adapted for printing and lithographing, adhesively fastened to a sheet of paper reinforced by cardboard or heavy stiff 10

15 paper for a substantial portion of its area including the peripheral portion, but having a substantial portion not so reinforced, said unreinforced portion having a strength such that it may be burst by the pressure of the fingers alone.

3. A frangible wall section adapted for use in a hermetically sealed, moistureproof container comprising a sheet of extremely thin polished metal foil, said metal foil having insufficient stiffness and strength for use as a wall section without reinforcement, adapted for printing and lithographing, adhesively fastened to a sheet of paper, reinforced by cardboard or heavy stiff 20

25 paper for a substantial portion of its area, including the peripheral portion, but having a substantial portion not so reinforced, said unreinforced portion having a strength such that it may be burst by the pressure of the fingers alone, the edges of said section being turned up to form 30 a flange, with the cardboard or heavy paper on the outside of the flange.

PAUL S. PITTINGER.
